US0D1046747S

(12) **United States Design Patent** (10) Patent No.: **US D1,046,747 S**
(45) Date of Patent: ** Oct. 15, 2024

(54) **VEHICLE WHEEL**

(71) Applicant: **GM GLOBAL TECHNOLOGY OPERATIONS LLC**, Detroit, MI (US)

(72) Inventor: **Ryan D. Skelley**, Berkley, MI (US)

(73) Assignee: **GM GLOBAL TECHNOLOGY OPERATIONS LLC**, Detroit, MI (US)

(**) Term: **15 Years**

(21) Appl. No.: **29/882,824**

(22) Filed: **Jan. 19, 2023**

(51) LOC (14) Cl. **12-16**

(52) U.S. Cl.

USPC **D12/211**
